LETTER OPENER

Alvin L. Holste, Portland, Oreg.

Application November 8, 1940, Serial No. 364,873

2 Claims. (Cl. 30—294)

My invention relates to new and useful improvements in a letter opener made of plastic material comprising a body or case and a lid, said letter opener using a cutter blade for the purpose of opening an envelope by cutting a small strip from edge of an envelope.

A still further object is to provide a device of the character of simple and practical construction which is efficient in use, relatively inexpensive to manufacture.

Other objects and advantages, reside in the details of construction as more fully here in after described and claimed, reference being had to the accompanying drawing forming part hereof, wherein, like numbers refer to like parts throughout, and in which—

Figure I is a front elevation view of letter opener with cutter blade shown in dotted outline mounted in position.

Figure II is an elevation sectional view taken on line II—II in the direction arrows are pointing in Figure I.

Figure III is an elevation sectional view taken on line III—III in the direction arrows are pointing in Figure I.

Figure IV is a lower end view of Figure I.

Figure V is a sectional view taken on line V—V in the direction arrows are pointing in Figure I.

Figure VI is a sectional view taken on line VI—VI in the direction arrows are pointing in Figure I.

Figure VII is a right hand elevation view of Figure I.

Figure VIII is a front elevation view of letter opener with cutter blade in operating position while cutting off the edge of an envelope shown in dotted outline.

Figure IX is a diagrammatic plan view of portion of an envelope shown in dotted outline.

Referring now to the drawing in detail.

The drawing in Figure I designates a body or case made of plastic material having a recess 13, on one side of the body or case for holding a cutter blade 11. The cutter blade extends down into the arm 15, which has a slot 16 for engagement of one corner of cutter blade 11, as shown in dotted line in Figure I.

The cutter blade is held in position by a lid 19, which is beveled on its edges as shown in Figure VI. The lid 19 is held in position by beads 18 which are on the inside edges of recess 13, as shown in Figure VI. The lid 19 has a concave portion 20 on one edge as shown in Figure V for the means of flipping out said lid.

An arm 15 running parallel with the body or case and said arm 15 is made of two pieces of plastic material having a slot 16 for a cutter

blade. The two pieces are attached together by projections 17 inserted into the holes in the other part of arm as shown in the drawing Figure II.

The groove 14 acts as a gauge when envelope is being cut open as shown in Figure VII.

The Figure IV is shown as bottom end view of letter opener with slot 16, which is used for end of cutter blade 11 as shown in Figure IV and Figure I.

10 Figure VII is an end view of letter opener with cutter blade 11 in operating position and 21 is an envelope shown by dotted lines in position in Figure VII and being cut open when being pulled along in groove 14.

15 The dotted line in Figure VIII designates edge of envelope 10, being cut off by cutter blade 11 and dotted line 21 is body of envelope as shown in Figure VIII or Figure IX. The 21 in Figure IX is a portion of an envelope with the edge of envelope 10 partly cut off by cutter blade 11.

20 From the foregoing it will be apparent that to open an envelope the latter is inserted into groove 14 and merely by pulling letter opener along edge of envelope, a small strip is taken off, leaving the envelope opened.

25 It is believed the details of construction, advantages and manner of use of the device will be readily understood from the foregoing, without further detailed explanation.

30 Having thus described the invention, what I claim is:

1. A letter opener for opening an envelope or the like, said opener comprising of a body or case made of plastic material, and having a recess on one side of body or case in proportion, and adapting for engaging a cutter blade, and said recess having beads on its inner sides for retaining a lid, and said lid being made of plastic material, and having its edges beveled for a frictional engagement in the recess of said body or case.

35 2. A letter opener for opening an envelope or the like, said opener comprising of a body or case made of plastic material, and having a recess on one side of said body or case in proportion, and adapted for engaging a cutter blade, and said recess having beads on its inner side for retaining a lid, and said lid being made of plastic material, and having its edges beveled for a frictional engagement in the recess of said body or case, and an arm extending from one edge of said body or case, and being formed of two pieces of plastic material, and one piece being attached to the other by the means of projections on one arm inserting into the holes in the other arm, and a slot being formed in said arm for engaging end of a cutter blade.

ALVIN L. HOLSTE.
